UNITED STATES PATENT OFFICE.

JAMES L. CLARKE, OF CHICAGO, ILLINOIS.

DESIGN FOR A CLOCK OR WATCH DIAL.

SPECIFICATION forming part of Design No. 31,501, dated September 12, 1899.

Application filed July 13, 1899. Serial No. 723,740. Term of patent 7 years.

To all whom it may concern:

Be it known that I, JAMES L. CLARKE, a subject of the Queen of Great Britain, residing at Chicago, in the county of Cook and State of Illinois, have invented and produced a certain new and original Design for Clock and Watch Dials, of which the following, in connection with the accompanying drawing, is a full, clear, and exact specification.

10 The said drawing represents a face view of a clock or watch dial, showing my design.

The leading features of my design consist of the clock or watch dial A and a series of pictures or busts surrounding the dial A, and 15 each of the said busts being arranged opposite and corresponding with one of the whole hours of the dial.

The dial A is circular and is surrounded by or bears two marginal rings or concentric circles B C, between which the numerals indicating the whole hours are situated, and surrounding the circles B C is an annular space or background D, within which are situated

a number of ellipses E, the same being twelve in number and arranged opposite the numerals indicating the whole hours, respectively, and in each of the ellipses E appears the head or bust of an army or naval officer and other dignitaries.

25 On the dial A above the center appears an ellipse F, larger than the ellipses E, and within this ellipse F appears the head or bust of a naval officer, while at the lower side of the dial A appears the representation of a battle-ship.

30 Crossing each other at the center of the dial A are a sword G and musket H.

Having thus described my invention, what I claim as new therein, and desire to secure by Letters Patent, is—

35 The design for a clock or watch dial substantially as herein shown and described.

JAS. L. CLARKE.
